UNITED STATES PATENT OFFICE

GUSTAF E. ANDERSON, OF BROCKTON, MASSACHUSETTS

MACHINE FOR ATTACHING ORNAMENTS TO SHOES

Application filed May 6, 1928. Serial No. 107,140.

This invention relates to machines for attaching buckles and other similar ornaments to the front or vamp portions of shoes and while primarily designed for this purpose it may also be used for various other kinds of work.

In the shoe manufacturing industry, it has been and now is customary in some styles of shoes, especially oxfords, pumps and the like, to improve the appearance of the shoes by attaching buckles, rosettes or other forms of ornaments to the front or vamp portions of the shoes. This work is necessarily done after the shoes are finished and heretofore has always been done by hand which has involved a comparatively large expense in view of the character of the operation and much waste of time.

The main object of my invention is the provision of a machine for rapidly and efficiently attaching buckles or other ornaments to shoes in a practically finished condition.

To this end, my invention contemplates a machine having a work-supporting member adapted for supporting a shoe in such position that its vamp portion may be operated upon for the attachment thereto of the ornament. This member may be of any suitable form but preferably is in the form 20 of an arm having a clear and unobstructed space therearound and of sufficiently small diameter to enter the opening in a shoe and project into the forepart; the main portion 25 of the arm being inclined downwardly and its end being turned horizontally. This construction permits a finished shoe to be mounted on the end of the arm in a substantially horizontal position, the end of the arm projecting into the forepart of the shoe 30 and supporting the vamp portion thereof, the heel of the shoe being raised upwardly 35 behind the inclined main portion of the arm.

The operating instrumentalities for attaching the ornament to the shoe may be mounted on an overhanging arm in position to operate upon the shoe and in the form of the invention herein shown comprises means 45 for stitching the ornament to the shoe by what is commonly termed zigzag stitching.

Another object of the invention is the pro-

vision of means for automatically stopping the machine at the conclusion of a pre-determined sequence of operations so that after the machine is started for attaching an ornament to a shoe, it will at the conclusion of the attaching operation automatically stop. 55

In attaining this object of the invention, I provide means set in motion by the starting of the machine for rocking the needle bar laterally to lay a pre-determined number of 60 stitches and for throwing out the clutch to stop the machine upon the conclusion of the pre-determined number of stitches. These means are so arranged that temporary pressure on a treadle will start the machine in 65 operation after which it continues operating through the cycle and then automatically stops. By holding the foot treadle the machine may be operated continuously but in 70 work of this character it is of advantage to secure automatic stopping at the conclusion 75 of each attaching operation.

A further object of the invention is the provision of means for operating from the main shaft of the machine such cooperating 75 instrumentalities as may be mounted in the end of the lower or work supporting arm.

To this end, may be mounted within the work supporting arm means for transmitting movement from the main shaft of the machine to the instrumentalities in the end 80 of the lower arm.

Other objects of the invention will be more specifically set forth and described 85 hereinafter.

In the accompanying drawings illustrating one embodiment of my invention, Figure 1 is a side elevation of a machine constructed and adapted to be operated in accordance with the invention; Fig. 2 is a plan view of the same; Fig. 3 is a longitudinal vertical sectional view of the machine; Fig. 4 is a vertical cross-sectional view on line 4-4 in Fig. 2; Fig. 5 is a sectional view 95 looking from right to left in Fig. 1, showing the two clutch members and clutch mechanism in elevation with the clutch thrown in; Fig. 6 is a similar view of the idler pulley wheel and expansion ring with the clutch 100

thrown out; Fig. 7 is a front end elevation of the machine looking from right to left in Fig. 1; Fig. 8 is a rear end elevation looking from left to right in Fig. 1; Fig. 9 is a 5 diagrammatic view of the cam for rocking the needle bar illustrating its operation; Fig. 10 is a diagrammatic view of the stitching laid by the needle for one full revolution of said cam; and Fig. 11 is a central vertical 10 sectional view of the clutch mechanism with the clutch pin out.

Referring to the drawings illustrating one embodiment of my invention, the frame of the machine comprises a hollow column or 15 standard 14 carrying a work-supporting member preferably in the form of a downwardly inclined hollow arm 16 having its end portion 18 turned horizontally and an overhanging hollow arm 20 adapted for supporting operating instrumentalities (Fig. 1). The frame is preferably made in one casting, the head of the column being turned over laterally to form the overhanging arm and the work supporting arm projecting 25 downwardly from the junction of the column and upper arm, the ends of the two arms being arranged in co-operative relation. My invention is not to be limited, however, to the specific form of frame shown since it 30 may be made in any suitable form so long as the work-supporting member is of sufficiently small diameter to project into the forepart of the shoe and is surrounded by a clear and unobstructed space permitting a 35 shoe to be mounted on the end thereof with its heel portion raised, to present its vamp portion in proper position to be operated upon.

For fastening the machine to a suitable 40 table or support 22 the base portion of the column 14 may be provided with ears 24 bored to receive screws or bolts. On one side the column is provided with a rectangular opening to give access to the interior of the frame, which opening may be 45 normally closed by a cover 25 having a finger-piece 26 to facilitate handling.

Although various forms of instrumentalities may be mounted on the end of the overhanging arm for performing different operations on finished shoes yet for attaching ornaments to shoes the machine is shown 50 equipped with means for sewing the ornaments to the shoes by what is commonly 55 termed zigzag stitching. The end of the arm 20 is in the form of an enlarged open housing 28 having internally projecting pins 29 and 30 set in its top and bottom walls respectively which serve as bearings for the 60 ends 31 of a vertical yoke 32 adapted for a lateral swinging movement on said pins. The pin 30 is made adjustable by being threaded through the top wall of the housing 28 and is held in adjusted position by a set 65 nut 33. The main portion of the yoke lies

outside the open housing 28 and is bored vertically to receive a needle-bar 34 adapted for carrying a needle 35 in its lower end.

For reciprocating the needle-bar 34, a portion 36 of the yoke housing is offset to expose 70 a part of that bar to permit it to be connected to the main shaft 38 of the machine which is rotatably mounted in the overhanging arm in bearings 40 and 41 formed in the front end of said arm and rear wall of the 75 column and in an intermediate bearing 42 carried by a web 43 (Fig. 3). Fixed on the front end of the main shaft is a crank-disk 45 carrying a pin 46 eccentrically positioned thereon, said pin being connected to said bar by two links 47 and 48 pivotally connected together at 49 and the link 48 being pivotally connected at its other end to a collar 50 secured to the needle bar. The rotation of the main shaft and crank-disk 80 through the medium of the two links imparts a reciprocatory movement to the needle-bar.

In order to lay stitches from one side to the other or in a zigzag fashion, means are 85 provided for oscillating the needle-bar housing laterally on the pins 29 and 30 as pivots. The upper end 31 has a lateral extension or arm 55 which is connected by a link 56 to a pin 57 carried by a plate 58 pivotally mounted at one end on a pin 59 set in the top of the overhanging arm 20. The plate 58 swings laterally on the pin 59 as a pivot to oscillate the needle-bar housing and to vary the extent of said oscillation the pin 57 is set in a 90 curved groove 60 in the top face of the plate, the radius of said curve being the link 56. The pin 57 is dovetailed in the groove, the sides of which are undercut, and is held in adjusted position therein by a nut 62 which when tightened causes a binding 95 action between the base of the pin and the undercut sides of the groove. By moving the pin in the groove the effective throw of the link 56 may be varied.

The oscillation of the plate 58 is controlled by a horizontal circular cam 65 having a cam-path 66 in its upper face to receive a roll 67 fastened to the under face of the plate 58 (Figs. 3 and 4). The cam is fixed to a vertical cam-shaft 70 rotatably mounted in a portion 71 of the overhanging arm (Fig. 4) and adapted to be rotated by the main shaft through the instrumentality of a worm 73 on the main shaft which meshes with a worm gear 74 secured to the cam-shaft by a pin 75. A collar 76 may be mounted on said shaft between said worm gear and the cam.

The cam-path 66 (Fig. 9) is laid out to cause an oscillation of the plate 58 and thereby a lateral oscillation of the yoke 32 and needle-bar to lay zigzag stitching for securing the ornament to the shoe. The relative number of revolutions of the main

shaft for each revolution of the cam may be regulated by varying the pitch of the worm 73 and the teeth of the worm gear 74 but in the form shown, the cam is designed for one revolution for each ten revolutions of the main shaft thereby laying ten stitches on each revolution of the cam. The needle-bar makes one complete up and down reciprocating movement for each revolution of the main shaft. In Figure 9 the cam path is shown laid out diagrammatically for accomplishing the ten lateral oscillating movements of the needle-bar yoke housing necessary for the laying of the ten stitches on each complete revolution of the cam.

Upon the extreme end of the work supporting arm 16 is fixed a work supporting plate 80 provided with suitable apertures for the passage of the needle and cooperating with the needle is a rotary hook 81 keyed to a hook shaft 82 rotatably mounted in the end 18 of the work supporting arm, the hook being held in place thereon by a washer 83. The hook shaft is rotated from the main shaft through the instrumentality of a transmission shaft 85 supported in an inclined position in suitable bearings 86 and 87 the bearing 86 being supported by a web portion of the frame and the bearing 87 being in the form of a bushing which is held in a web portion 88 of the lower arm by a set nut 89. Upon the inner end of the hook shaft is a bevelled gear 90 meshing with a bevelled gear 91 on the lower end of the transmission shaft and on the upper end of the latter is fixed a bevelled gear 92 meshing with a suitable gear 93 mounted on the main shaft 38, all of these gears being keyed to their respective shaft in any suitable manner.

Any suitable form of clutch may be employed for transmitting movement from a source of power to the main shaft of the machine and one form is shown comprising a hollow idler pulley wheel 100 open on its inner face and a member 101 fixed to the main shaft. The end of the main shaft is supported by a curved bracket 102 secured at its lower end to the rear end of the frame of the machine by screws 103, the members of the clutch being mounted on said main shaft between said bracket and the bearing 41. The two members of the clutch are locked together for rotating the main shaft by means of a frictional expansion ring 105 carried by a pin 106 set in the fixed member 101, and an expanding member 107. The expansion ring 105 lies within the hollow pulley and is supported at its top on the pin 106 and is split at its lower end, each of said ends being provided with an upwardly extending curved lug or ear 109 between which is located the expansion member 107. This latter member is loosely mounted between the ears 109 and is elliptical in cross section

with its long axis normally vertical as shown in Fig. 6 but when turned sideways to the position shown in Fig. 5 it engages and presses the two ears 109 apart and expands the ring 105 to frictionally engage the inner surface of the periphery of the pulley wheel 100 to lock the two members of the clutch together to turn the main shaft.

For turning the expansion member, it is provided on its top with an upwardly extending ear 110 adapted to be engaged by a similarly formed ear 111 on a locking lever 112 provided with an integral lateral pin 114 loosely mounted in the clutch member 101 and extending therethrough and having fixed on its reduced end a U-shaped arm 115. The locking lever lies within the hollow pulley and is normally held in a locking position by a spring 117 secured at its lower end to the free end of the locking lever 112 and at its upper end to a pin 118 set in the clutch member 101. The spring is under tension at all times so that its tendency is always to pull upwardly the locking lever and to throw the expansion member sideways. The U-shaped arm 115 which is integral with the locking lever lies on the opposite side of the clutch member 101 and serves as means for operating the locking lever against the tension of spring 117 to release the expansion member and to disconnect the two clutch members.

For controlling the clutch, a clutch pin 120 is loosely mounted in a bearing 121 formed on the machine frame and when thrown upwardly engages a radial shoulder 122 formed on the clutch member 101 by cutting it away in one side (Fig. 5) on the line 123. To reinforce the shoulder 122 to withstand impact with the clutch pin, the clutch member 101 is provided with a thickened area 125 extending from the hub outwardly on a curve in order not to interfere with the movement of the U-shaped arm 115 which surrounds its outer portion.

The operation of the clutch is extremely simple. When the clutch pin is in engagement with the shoulder 122, the parts are in the position shown in Fig. 6, the arm 115 being shown in broken lines, its end being against the clutch pin. In this position, the idler pulley is running wild, the expansion member being in its normal position, the locking lever being down and the arm 115 being in raised position. The withdrawal of the clutch pin in a downward direction releases the arm 115 and the spring 117 thereupon draws up the locking lever into the position shown in Fig. 5 and turns the expansion member to expand the ring 105 to make a frictional contact between the two members of the clutch; that is, the pulley and the fixed member 101. The raising of the locking lever throws the arm 115 downwardly so that its end projects beyond the

shoulder 122. When the clutch pin is forced in again the cut-away portion of the fixed member on line 123 permits the pin to enter into stopping position and as the clutch revolves, the end of the arm 115 first engages the clutch pin and stops. The continued revolution of the clutch while the arm 115 stands still causes the locking lever 112 to be turned downwardly against the tension 10 of the spring 117 to release the expansion member and to disconnect the two members 15 of the clutch so that when the shoulder 122 on the member 101 engages the clutch pin it stops the main shaft and the machine. 20 To prevent any rebound of the member 101 on its impact on the clutch pin an upwardly extending arm 130 is pivotally mounted on a screw 131 in the frame in position to engage a shoulder 132 cut into the edge of the member 101. A spring 133 held at one end by a screw 134 bears at the other end against the arm 130 to press it inwardly for engagement with said shoulder and to throw said arm outwardly when the clutch-pin is pulled 25 out, a roll 136 carried by the pin engages the lever in such position that any downward movement of the clutch-pin pushes the arm out of engagement with the said shoulder. To prevent the entrance of dirt or other foreign matter to the interior of the clutch a cover plate 138 is fastened to the inner face of the fixed member 101.

The head 140 of the clutch-pin may be enlarged to form a shoulder adapted to engage the bearing 121 when the clutch-pin is pulled out to limit the withdrawal and may also have a side extension 142 extending upwardly and adapted to bear against the hub of the fixed member 101 to support the head 40 of the clutch-pin under the impact of the shoulder 122 in the stopping of the machine (see Fig. 8).

For controlling the movement of the clutch-pin in relation to the two members 45 of the clutch there is provided resilient means for normally holding the clutch-pin in an inoperative position and means adapted to be operated by the cam controlling the movement of the needle bar 50 housing for throwing the clutch-pin into operative position to stop the machine after a predetermined number of stitches have been laid. Any suitable means may be provided for accomplishing this end and one such 55 means is shown in the drawings comprising a spring 144 for normally holding the clutch-pin out of engagement with the fixed member of the clutch and a bell-crank lever 146 for throwing the clutch-pin into operative position against the tension of the 60 spring. The spring 144 is connected at its upper end to a pin 148 set in the lower end of the clutch-pin and at its lower end to a pin 149 set in the frame of the machine, the 65 spring being under tension at all times. The

bell-crank lever 146 is pivotally mounted on a stud 152 fixed in the column of the frame and one arm thereof bears against the lower end of the clutch-pin and the other arm is pivotally connected by a screw 154 to a rod 70 155 which at its other end is pivotally connected to a bell-crank lever 157 rotatably mounted on a screw pin 158 threaded in the end of the overhanging arm and below the cam 65. The other arm of the bell-crank 75 lever 157 has rotatably mounted thereon a sleeve 160 carrying an integral arm 161 extending upwardly in an oblique direction to engage a block 163 fixed to the under side of the cam. The sleeve 160 also carries a horizontal arm 165 extending outwardly and adapted to be connected to a foot treadle (not shown).

These parts are shown in Fig. 3 in normal position with the machine ready to be started, the clutch-pin being in operative position and the arm 161 in engagement with the block 163. By depressing the foot treadle attached to the arm 165, that arm is depressed turning the sleeve on the bell-crank lever and pulling the arm 161 out of engagement with the block. The spring 144 thereupon pulls the clutch-pin out of engagement with the fixed member of the clutch and the movement of the clutch-pin turns the bell-crank lever 146 downwardly and through the connecting rod 155, the bell-crank lever 157 from right to left and the machine starts in operation. The turning of the bell-crank lever 157 from right to left turns that arm on which the sleeve 160 is mounted upwardly and when the pressure is released on the treadle a spring 167 draws the arm 161 inwardly against a stop 168 in position to be engaged by the block 163 on the under face of the cam at the end of the first complete revolution. The sleeve 160 being in a raised position, it throws the end of the arm 161 from left to right so that it is engaged by the block in advance of its normal position and upon such engagement, the block carries the arm forward thereby turning the bell-crank lever 157 from left to right and through the connecting rod 155, the bell-crank lever 146 upwardly to throw the clutch-pin into locking position and upon the stopping of the machine the block on the cam has returned the connected parts to the position shown in Figure 3.

For holding the buckle or other ornament to be attached to the shoe when the machine is used for that purpose a holding device of the general form of construction and operation disclosed in United States Letters Patent No. 1,529,286 issued to me March 10, 1925 for buckle holding attachment may be employed. This device is designated generally by the numeral 170 and since it forms no part of the present invention a description of it is not necessary. The said patent may 130

be referred to for a complete description of its construction and mode of operation.

The buckle holding device 170 is fastened to the lower end of a vertical presser-bar 5 loosely mounted in the open housing 28 and on one side thereof. For raising and lowering the presser-bar to permit work to be removed from or placed on the work-support a cam 172 in the form of a quadrant 10 is provided for engaging a roll 173 carried by a screw 174 threaded into the presser-bar. The cam has a cornerwise lateral pin 175 on which is fixed a rocking lever 176 for turning the cam. A helical spring 180 on 15 the presser-bar abutting at its upper end a hollow screw 181 threaded through the top wall of the housing 28 and at its lower end a collar 182 formed on the presser-bar, is under compression and holds the presser-bar in a downward position with the roll 173 20 in engagement with the cam. The presser-bar is therefore raised by the operation of the cam and when the latter is turned in the opposite direction the spring forces the 25 presser-bar downwardly to follow the cam.

To permit operation by a foot-treadle the two ends of the rocking lever 176 may be connected by cords or chains 185 and 186 to the two ends respectively of a treadle 184 30 pivoted midway on a support 187. The rocking of the treadle by the operator raises and lowers the presser-bar. The pressure of the spring on the presser-bar may be regulated by turning the hollow screw 181 with 35 a wrench or similar instrument and for this purpose it is provided with a squared head.

In the use of the machine a shoe 190 is placed on the work-supporting arm in the position shown by broken lines in Fig. 3 in 40 which the end of the arm projects into the forepart of the shoe and supports its vamp at the point where the buckle or other ornament is to be attached. To secure this position of a finished shoe it is essential that 45 the heel portion of the shoe be raised and the inclination of the main portion of the arm allows this to be done. After the shoe is properly positioned on the end of the work-supporting member, the operator inserts the 50 buckle or other ornament in the holding device and lowers the presser-bar by manipulation of the treadle thereby clamping the shoe and locating the buckle thereon. The 55 starting of the machine is effected by another treadle and the needle then lays the predetermined number of stitches in zigzag fashion over the center or other suitable portion of the buckle to secure it to the forepart of the shoe. In the machine herein 60 illustrated, the cam which operates the needle-bar housing is arranged to lay ten stitches in one complete rotation, the 65 stitches being of the form shown in Fig. 10 and the machine then stops. The thread

is cut, the presser-bar raised and the shoe removed.

It will be observed that the work of attaching buckles or other ornaments to shoes is very easily and expeditiously accomplished 70 with the use of my machine and a large saving in time and labor over the present day methods is accomplished.

Although the cam 65 for oscillating the needle-bar housing is designed to lay ten 75 stitches in one complete revolution, as shown in Fig. 9 where the respective stitches are numbered, the intervening portions of the cam path covering the upward movement of the needle, it is apparent that the cam may 80 be designed for a greater or a lesser number of stitches.

It is further to be understood that my invention is not to be limited to the specific form herein shown and described but may 85 be embodied in various other forms all within the purview of the invention as set forth in the following claims.

What I claim is:

1. A machine of the character described, 90 comprising a frame made up of an overhanging arm carrying a main shaft and operating instrumentalities, a lower work-supporting arm thereunder having its end of a diameter sufficiently restricted to permit a shoe to be mounted thereon with its vamp uppermost and in position to be operated on by the instrumentalities on said overhanging arm, said arm being bent upwardly 95 a short distance from its end to permit the heel of the shoe to be raised back of said end, operating instrumentalities carried by the end of said lower arm, a short shaft rotatably mounted in the bent upwardly end of said arm and a transmission shaft rotatably mounted in the oblique portion of said arm for transmitting rotary movement from 100 said main shaft to said short shaft.

2. A machine of the character described 105 having, in combination, a frame comprising a column, an overhanging arm extending laterally from said column and adapted for carrying a main shaft and operating instrumentalities on its end, a lower arm in vertical alignment with said overhanging arm 110 and extending obliquely downwardly from the junction of said column and said overhanging arm and having its end turned horizontally under the end of said overhanging arm and a work support mounted on 115 the horizontal end of said lower arm, operating instrumentalities carried by the end of said lower arm, a short shaft mounted in the horizontal end of said lower arm and a transmission shaft rotatably mounted in 120 the oblique portion of said arm for transmitting rotary movement from said main shaft to said short shaft.

3. A machine of the character described 125 comprising a frame made up of an over-

3 hanging arm carrying a main shaft and operating instrumentalities for attaching ornaments to shoes, a lower work supporting arm extending obliquely downwardly and having its end turned horizontally for holding a shoe in position to have ornaments attached to the forepart thereof; the longitudinal axes of said overhanging arm and said lower arm lying in the same vertical plane, a short shaft rotatably mounted in the horizontal end of said lower arm, operating instrumentalities on the end of said lower arm and a transmission shaft rotatably mounted in the oblique portion of said lower arm for transmitting rotary movement from said main shaft to said short shaft.

4. A machine of the character described comprising a column, an overhanging arm extending laterally from said column and carrying a main shaft and operating instrumentalities for attaching ornaments to shoes, a lower arm extending obliquely downwardly and having its end turned horizontally for supporting a shoe in position to have ornaments attached to the forepart thereof, the longitudinal axes of said overhanging arm and said lower arm lying in the same vertical plane, a short shaft rotatably mounted in the horizontal end of said lower arm, operating instrumentalities on the end of said lower arm and a transmission shaft rotatably mounted in the oblique portion of said lower arm for transmitting rotary movement from said main shaft to said short shaft.

5. A machine of the character described comprising a frame made up of an overhanging arm carrying a main shaft and on its end instrumentalities for operating on shoes, a lower work supporting arm thereunder, said lower arm extending obliquely downwardly and having its end turned horizontally, the longitudinal axes of said overhanging arm and said lower arm lying in the same vertical plane and the said end of said lower arm having a clear and unobstructed space therearound and being of sufficiently small diameter to permit a shoe to be mounted thereon with its forepart in position to be operated upon by the instrumentalities on the end of said overhanging arm, a short shaft rotatably mounted in the horizontal end of said lower arm, operating instrumentalities on the end of said lower arm and a transmission shaft rotatably mounted in the oblique portion of said lower arm for transmitting rotary movement from said main shaft to said short shaft.

6. A machine of the character described comprising a base, a column extending upwardly therefrom, an overhanging arm extending laterally from the top of said column, a main shaft in and operating instrumentalities on the end of said overhanging

arm for attaching ornaments to shoes, a lower arm extending obliquely downwardly under said overhanging arm and having its end turned horizontally for supporting the work, the longitudinal axes of said overhanging arm and said lower arm lying in the same vertical plane, a short shaft rotatably mounted in the horizontal end of said lower arm, operating instrumentalities on the end of said lower arm and a transmission shaft rotatably mounted in the oblique portion of said lower arm for transmitting rotary movement from said main shaft to said short shaft.

7. A machine of the character described comprising a frame made up of an overhanging arm carrying a main shaft and instrumentalities for operating on shoes, a lower work supporting arm thereunder extending obliquely downwardly and having its end turned horizontally, said end being of sufficiently small diameter to permit a shoe to be mounted thereon with the vamp portion uppermost and the longitudinal axes of said overhanging arm and said lower arm being disposed in the same vertical plane, a short shaft rotatably mounted in the horizontal end of said lower arm, operating instrumentalities mounted on the end of said lower arm and a transmission shaft rotatably mounted in the oblique portion of said lower arm with bevelled gear connections to said main shaft and said short shaft for transmitting rotary motion from said main shaft to said short shaft.

8. A machine of the character described comprising a frame made up of an overhanging arm carrying a main shaft and operating instrumentalities for attaching ornaments to shoes, a work supporting member of sufficiently small diameter to project into the forepart of a shoe and having a clear and unobstructed space about its end and back to permit a shoe to be mounted on the said end with its heel portion raised sufficiently to bring said shoe into an approximately horizontal position on said member with the vamp portion uppermost, the longitudinal axes of said overhanging arm and said work supporting member being disposed in the same vertical plane, a short shaft rotatably mounted in the horizontal end of said lower arm, operating instrumentalities mounted on the end of said lower arm and a transmission shaft rotatably mounted in the oblique portion of said lower arm with bevelled gear connections to said main shaft and said short shaft for transmitting rotary motion from said main shaft to said short shaft.

9. A machine of the character described having, in combination, a column, an overhanging arm extending laterally from said column, a main shaft rotatably mounted in said overhanging arm, operating instru-

mentalities on the end of said arm, a lower arm below said overhanging arm and in vertical alignment therewith, the end of said lower arm being horizontal and the main portion of said lower arm being oblique, a work support mounted on the end of said lower arm, said work support and the horizontal end of said lower arm being of sufficiently small diameter to project into the forepart of a shoe and said oblique main portion of said lower arm permitting the heel portion of a shoe to be raised to bring that portion thereof on the work support into horizontal position, a short shaft rotatably mounted in the horizontal end of said lower arm, operating instrumentalities carried by said shaft and a transmission shaft mounted in the oblique portion of said lower arm and having gear connections with said main shaft and said short shaft to transmit rotary motion from the former to the latter.

In witness whereof, I hereunto set my hand this twentieth day of April 1926.

GUSTAF E. ANDERSON.
